UNITED STATES PATENT OFFICE.

JAMES R. SHAFFER, OF HUNTINGTON, INDIANA; JANE SHAFFER, ADMINISTRATRIX OF SAID JAMES R. SHAFFER, DECEASED.

PICKET-WIRING MACHINE.

SPECIFICATION forming part of Letters Patent No. 479,311, dated July 19, 1892.

Application filed March 2, 1892. Serial No. 423,520. (No model.)

To all whom it may concern:

Be it known that I, JAMES R. SHAFFER, a citizen of the United States, residing at Huntington, in the county of Huntington and State 5 of Indiana, have invented new and useful Improvements in Picket-Wiring Machines, of which the following is a specification.

My invention relates to a device for use in the construction of that class of fences which 10 are formed of wooden or other pickets and wire stringers or stretchers.

The object of the invention is to provide a device through the instrumentality of which the wire stringers or stretchers of the fence 15 may be uniformly twisted and the relative position of the pickets and wires be gaged with accuracy and dispatch.

Referring to the accompanying drawings, Figure 1 is a side view of the device complete. 20 The dotted lines show the position of the operating-lever as when the device is first applied to the wires, while the full lines show the position of the said lever after the wires have been given one full twist. Fig. 2 is a 25 perspective view of a portion of a fence the wire stringers of which are twisted as with my improved device. Fig. 3 is a perspective view from the inner side of one of the side plates of the frame. Fig. 4 is a perspective 30 view of the twisting-wheel detached. Fig. 5 is a perspective view of the upper part of the device, showing one of the bearing-plates or cross-bars and gage connected therewith.

The frame of the device is composed of two 35 plates A B, which are somewhat triangular in form and adapted to be connected together by means of bolts c d e, as shown. Bosses or projections c' d' e' are made on the inner surface of each plate, where the bolt-holes 40 are located, in order that when the plates are placed together sufficient space will be left between same for the reception of the gear portion of the mechanism. The rear ends of the plates, or that portion of the said plates 45 in which the bolt e is located, are rounded and provided with indentations, as shown at f g, while between the bolts c and d each plate is provided with a circular hole h, having an opening at the front edge thereof, as 50 shown at i, for purposes hereinafter fully described.

The forward ends of the plates A B terminate in lugs k l, having perforations therein for the reception of bolts or screws m n, whereby cross-pieces of wood or other material x x' are secured thereto to rest against the pickets while securing same. 55

The letter O designates a gear-wheel having circular side projections p q, which are adapted to fit and operate in the openings h 60 of the plates A B. This wheel is provided with a radial slot s, which is designed to register with the openings i of the frame-plates. The slot s is carried well beyond the axis of the wheel and is intended for receiving the 65 fence-wires and to twist the same during the operation of the device.

T is a semicircular toothed wheel the center or hub of which is bored to fit and operate on the bosses surrounding the inner portions of the rear bolt e, so that its teeth t shall engage those of the wheel O, as clearly shown 70 in the drawings.

An operating-lever u projects rearwardly from the hub of the toothed wheel T. This 75 lever is provided near the fulcrum thereof with a longitudinal slot (shown in dotted lines at t' in Fig. 1) to receive the inner projections of a pair of sliding plates or catches t'', which are arranged at opposite sides of 80 the lever, and thus held by a screw t''', which is inserted in a hole made through the aforesaid plates and inner projections thereof. A rubber or other spring t'''' is fitted in the recess t'', so as to continually press the sliding 85 plates toward the rear edges of the frame-plates A B, and thus alternately engage the indentures f g therein as the lever is moved to an upper or lower position. For this purpose the impinging ends of the sliding plates 90 should be so shaped as to neatly fit the indentures or recesses aforesaid.

To insure an even space between the pickets as they are successively secured in position, a gage-block a is fastened by a screw or 95 other device to the central front portion of one of the cross-pieces x at the front of the device.

The operation of my device is as follows: The pickets are first placed in position with 100 the wire stringers arranged in front and rear thereof. The device is then applied so that

the radial slot of its twisting-wheel shall engage the aforesaid wire stringers, the cross-pieces α shall rest against the face of the pickets, and the gage-block enter between the latter. The lever during this time being in its upper position is now pressed downward as far as it will go, after which it is moved backward until its sliding plates or catches shall engage the lower indentations of the frame-
10 plates, which brings the slot of the twisting-wheel in line with the open part of the frame, and thus permits of the removal of the device to secure in like manner the next picket.

Having described my invention, what I claim as new, and desire to secure by Letters Patent, is—

1. In a picket-wiring machine, the combination, with a suitable frame, of a gear-wheel having a radial slot and side journals, as described, a segmental rack adapted to engage the gear-wheel, and a lever connected with the rack for operating the same, substantially as set forth.

2. In a picket-wiring machine, the combination of a frame composed of two triangular

plates having perforated inner projections and securing-bolts, as described, the forward part of the frame having a slotted bearing and a radially-slotted gear-wheel journaled therein, an operating-lever with segmental rack pivoted in the rear part of the frame, indentures at the rear of the frame-plates, and the spring-actuated catches of the operating-lever, substantially as described.

3. The combination, in a picket-wiring machine, of a triangular frame having a slotted bearing and a radially-slotted gear-wheel journaled therein, an operating-lever with segmental rack pivoted in the rear of the frame, a pair of bearing-plates at the forward part of the frame, and a gage-block secured to one of the bearing-plates, substantially as and for the purpose described.

In testimony whereof I affix my signature in presence of two witnesses.

JAMES R. SHAFFER.
